(57) **CLAIM**

The ornamental design for a vehicle tail light cover, as shown and described.

DESCRIPTION

FIG. 1 is a front perspective view of a first embodiment of the vehicle tail light cover.

FIG. 2 is a back perspective view of FIG. 1.

FIG. 3 is a front view of FIG. 1.

FIG. 4 is a back view of FIG. 1.

FIG. 5 is a top view of FIG. 1.

FIG. 6 is a bottom view of FIG. 1.

FIG. 7 is a right side view of FIG. 1.

FIG. 8 is a left side view of FIG. 1.

FIG. 9 is front perspective view of a second embodiment of the vehicle tail light cover.

FIG. 10 is back perspective view of FIG. 9.

FIG. 11 is a front view of FIG. 9.

FIG. 12 is a back view of FIG. 9.

FIG. 13 is a top view of FIG. 9.

FIG. 14 is a bottom view of FIG. 9.

FIG. 15 is a left side view of FIG. 9; and,

FIG. 16 is a right side view of FIG. 9.

The broken lines are used to show unclaimed portions of the tail light cover and form no part of the claimed design.

1 Claim, 12 Drawing Sheets
